UNITED STATES PATENT OFFICE

2,530,520

PROPELLER HUB

Paul F. Hackethal, Cockeysville, and Romuald Karey, Baltimore, Md., assignors to Everel Propeller Corporation, Baltimore, Md., a corporation of Maryland

Application September 17, 1946, Serial No. 697,488

3 Claims. (Cl. 170—160.58)

1

This invention relates in general to propellers for aircraft and more particularly has reference to the construction of a hub for the mounting of blades of a variable pitch propeller.

Automatic pitch changing propellers have been developed in which the shanks of the blades are secured in flanged sleeves which are mounted for rotation within suitable sockets formed in the hub of the propeller. The construction of the blade shank-receiving-sleeves is such that the longitudinal axes of the blades are at an angle to the rotational axes of the sleeves with the result that the rotational position of the blades with respect to the hub determines the pitch of the blade and as a consequence the pitch angle of the blades is affected by various conditions encountered in flight. These conditions are principally the relationship of the aerodynamic forces acting on the blade, the centrifugal force acting on the blades, and the centrifugal force due to the counterweights secured to the blades.

While a high degree of perfection has been obtained in such propellers, both in construction and operation, certain difficulties have been encountered in the assembly and adjustment of the blades with respect to the hub and to each other and in balancing the propeller while still maintaining the individual weight and balance of the blades within such prescribed weight tolerances that a blade of a propeller may be replaced in service without the necessity of completely rebalancing the assembly.

Also in the prior constructions difficulty has been encountered in the sealing of the blade-shank-receiving-sleeves within the hub sockets with little frictional resistance to free rotation about their axes and with effective sealing. In addition, difficulty has been encountered in producing an effective seal, practical for its intended purpose, at low cost.

It is desirable to provide a connection between the blades of a propeller to insure movement in unison of the blades about the turning axes of their mounting sleeves to effect variations in pitch. Numerous devices for this purpose have been developed but for various reasons, such as excessive weight, disturbance of balance of the propeller assembly and excessive resistance to pitch varying movements of the blades, such prior devices have not been entirely satisfactory. Furthermore, the means for limiting pitch varying movements of the blades have been of various forms, but here again, difficulties due to disturbance of balance and excessive weight have been encountered.

2

The principal object of the present invention is to provide a propeller hub construction which is free from the above pointed out disadvantages inherent in the prior art.

5 Another object of the present invention is to provide a propeller hub construction for the mounting of the blades of an automatic variable pitch propeller in which the propeller blades have their shanks received in sleeves which in turn are mounted within sockets in the hub so as to permit free rotation of the sleeves within the hub and yet effectively seal the joint between the sleeves and the hub to prevent leakage of oil therethrough.

10 15 A further object of the present invention is to provide an improved mechanism for loading the bearings which serve to rotatably mount the blade-shank-receiving-sleeves within the hub of the propeller.

20 25 Still another object of this invention is to provide an improved bearing loading construction equipped with means for positively retaining the same in adjusted positions.

A still further object of this invention is to 30 35 provide an improved mechanism interconnecting the sleeves of the blades of the propeller for effecting uniform, synchronous movement of the blades about their rotary axes during pitch changing movements.

30 It is also an object of the present invention to provide an improved device for limiting the movements of the blade-shank-carrying-sleeves during pitch changing movements.

The present invention also has as an object 35 40 the combination and correlation of the features set forth in the preceding objects to provide a highly improved construction of the hub of an automatic variable pitch propeller.

With these and other objects in view, the present invention comprises the parts and combinations herein described and illustrated in the drawings.

40 In the drawings:
45 Figure 1 is a transverse sectional view taken through the blade-shank-receiving-sleeves and the portion of a propeller hub mounting, said sleeves constructed in accordance with the present invention, said view being taken on line 1—1 of Figure 2 of the drawings.

Figure 2 is a view taken transversely to the axis about which the propeller blades rotate during pitch changing movements.

Figure 3 is a side elevational view of a propeller 50 hub constructed in accordance with the present

invention, parts being broken away to illustrate detail of construction.

Figure 4 is a fragmentary sectional view illustrating in greater detail the construction and arrangement of the seals for preventing leakage of oil from the bearings within the hub.

Figure 5 is an enlarged detailed cross sectional view of a packing ring employed in the present invention.

As shown in the drawings, a propeller hub constructed in accordance with the present invention has been designated generally by reference character 1. The hub comprises a barrel 2 and a mounting flange 3 which serves to connect the barrel to a corresponding flange carried by a drive shaft of an engine. Flange 3 may be formed as an integral part of the barrel 2 or it may be secured thereto in any suitable manner such as by welding, brazing and the like. Barrel 2 has an integral bore 4 extending diametrically or transversely of the axis of rotation of the hub 1. This bore 4 is of substantially the same internal diameter throughout its length with the exception of a seat 5 provided intermediate its end portions and an inwardly extending flange 6 adjacent the seat.

The ends of bore 4 within the barrel 2 serve as sockets to receive sleeves 7 in which the propeller blade shanks are mounted. Adjacent each end of the bore 4 annular grooves 8 are provided for the reception of split resilient rings 9 which serve as blocking means to retain the sleeves within the bore 4.

Sleeves 7 are provided with internal threads 10 which are adapted to cooperate with the threaded shank portions of the propeller blades (not shown). The outer ends of the sleeves 7 are provided with cuffs 11 having a plurality of axially extending slits 12 to render said cuffs resilient. Surrounding the split ends of the cuffs are clamping bands 13 which are retained on the cuffs by means of small resilient snap rings 14. Clamping rings 13, as better shown in Fig. 3 of the drawings, include radially extending portions 15 through which suitable bolts 16 extend and serve to clamp the rings 13 and the radial extensions 15 in desired positions with respect to the cuffs 11 and the propeller blades carried therein. The extreme outer portions of the radial extensions 15 are provided with bores 18 for the reception of bolts by means of which counterweights (not shown) are secured to said extensions.

As clearly shown in Fig. 1 of the drawings, the inner ends of the sleeve 7 are provided with outwardly extending circumferential flanges 17. Immediately adjacent the flange 17, the exterior of each sleeve 7 is provided with a seat 18 for the reception of one race 19 of a ball thrust bearing assembly 19'. The other race 20 of said ball thrust bearing assembly has an external diameter approximating the internal diameter of the barrel 2. Lying in contact with the race 20 is a retaining ring 21 which cooperates with the snap ring 9 to retain the ball bearing assembly 19' and the sleeves 7 within the outer end of the barrel 2. This retaining assembly serves to effectively block any tendency for the sleeve 7 to move outwardly of the end of the barrel 2.

As more clearly shown in Fig. 4 of the drawings, the outer peripheral portion of one end face of the race 20 is provided with an annular recess 22 of a trapezoidal cross section for the reception of a similarly shaped packing ring 23. This packing ring cooperates with the inner surface of the barrel 2, with the surfaces of the groove 22 and

with the adjacent end face of the retaining ring 21 to provide an effective seal between these three elements.

The inner peripheral portion of the retaining ring 21 is provided with an annular groove 24 of rectangular cross section in the end face thereof, abutting the race 20. Positioned within the annular groove 24 is a packing ring 25 of a special construction as more clearly illustrated in Fig. 5 of the drawings. This packing ring has an inner peripheral portion 26 of cylindrical formation and end faces 27 and 28 which flare outwardly. Actually, the end face 27 may be plain but, in any event, the end face 28 is flared outwardly. It is preferable that the end face 28 be of greater extent than the face 27 to provide the configuration shown in Figs. 4 and 5 of the drawings. The outer peripheral surface 29 of the ring 25 is in the form of a circumferential groove or trench which cooperates with the resilient tensioning member which, as shown in the drawings, comprises a coil spring 30.

As illustrated in Fig. 4 of the drawings, the packing ring 25 is positioned within the annular groove 24 with the inner cylindrical face surrounding the sleeve 7 and with the outer peripheral portion extending into the groove 24. The coil spring 30 is then placed within the groove or trench 29 and placed under tension to compress the ring about the sleeve 7. The compression of the packing ring 25 serves to cause the outer peripheral portions of the end faces 27 and 28 to be pressed axially against the surfaces of the race 20 and the retaining ring 21 to provide an effective seal between these members and the sleeve 7.

By virtue of the provision of the sealing or packing rings 23 and 25 and the arrangement of the same within the grooves provided therefor, a seal is afforded which, while very effective for preventing the leakage of oil past the same, even under pressure created by centrifugal action on the oil during rotation of the propeller, nevertheless, does not provide excessive friction for retarding or resisting the free rotation of the sleeve 7 within the barrel 2.

In order to load the anti-friction bearings so as to eliminate any looseness in the assembly and to maintain the bearings loaded even when the propeller is stationary, the present invention contemplates the provision of an adjustable expansible assembly extending between the inner ends of the blade carrying sleeves 7. As best illustrated in Fig. 1 of the drawings, the inner ends of the sleeves 7 are bored to provide recesses 31 in which are received the outer race 32 of an anti-friction ball bearing assembly 32a. The inner race 33 of the ball bearing assembly of one of the sleeves 7 is fitted on to the outer of two telescopically mounted elements of an adjustable expansible device. Said outer element 34 is provided with a shoulder 35 to abut the inner end of the race 33 whereas the recess 31 is provided with a shoulder for engaging the outer end of the race 32. Element 34 is internally threaded for engagement with the externally threaded portion of the inner element 36. In addition to the threaded engagement between the outer and inner elements 34 and 36, said elements are provided with cooperating telescoping cylindrical surfaces.

Inner element 36 is provided with a seat 37 for the reception of the inner race 33 of a second ball bearing assembly 32a which is mounted within the recess 31 of the other blade receiving sleeve 7.

The threaded end of the outer telescopically mounted member is provided with a plurality of slots or serrations 38 which are best shown in Fig. 2 of the drawings. These slots or serrations serve as a means by which a tool or other device may be engaged with the element 34 to effect rotation thereof. The inner element 36 is provided with an inner bore of reduced diameter which is provided with a plurality of splines 39 by means of which said element 36 may be engaged with a wrench or other tool for effecting rotation thereof. By engaging the elements 34 and 36 with proper tools cooperating with the serrations 38 and the splines 39, said telescopically mounted threadedly interconnected elements may be rotated with respect to each other to vary the distance between their outer ends. By virtue of the interpositioning of the ball bearing assemblies 32a and 32b between the ends of the elements 34 and 36 and the ends of the sleeves 7, outward axial movement of the ends of the telescopically mounted elements will tend to force the sleeves 7 toward the outer ends of the barrel 2 and thereby load the anti-friction bearings 19' positioned between the sleeves and said barrel.

After adjustment of said elements 34 and 36 with respect to each other, they may be positively secured by the insertion of a bolt-like locking element 40 having a splined outer surface cooperating with the splines 39 and a head 41 engaging with the slots or serrations 38 of the element 34. The head 41 is retained within the slots 38 by placing a nut 42 on the threaded end of the bolt-like element 40. Suitable lock washers or other securing means may be provided for retaining the nut in place on the bolt-like locking member 40.

After the telescopically mounted elements 34 and 36 have been adjusted with respect to each other to properly load the bearings 19', the openings through sleeves 7 affording access to the elements 34 and 36 may be closed by suitable closure members 43 which are in the form of discs having peripheral portions adapted to be received within counterbores formed in the inner ends of the sleeves. Interposed between the bottoms of said counterbores and the discs 43 are suitable sealing elements 44 against which the edges of the discs are pressed and retained by split snap retainer rings 45. Small knobs 46 may be associated with each of the discs 43 to facilitate the placing and the removal of the same from closing position. By providing the discs 43 sealed within the inner openings of the sleeves 7, oil or other lubricant within the barrel 2 may be retained therein and prevented from creeping out between the sleeve 7 and the shanks of the propeller blades mounted therein.

On the inner end of each of the sleeves 7, there is eccentrically mounted a pin 47 which may be screw-threaded or otherwise anchored in place. Pins 47 are located with respect to each other as illustrated in Fig. 2 of the drawings. A pair of links 48 are each connected at one end to one of the pins 47 and are connected at their other end both to a wrist pin 49 which extends through a plunger or piston 50. The plunger or piston 50 is mounted within the bore of a small cylinder 51 which extends radially with respect to the barrel 2. Although the cylinder 51 is shown located diametrically with respect to the mounting flange 3, said cylinder 51 may be located at any position about the periphery of the barrel 2. As a matter of fact, it may even

be mounted within the connection between the barrel 2 and the flange 3. The only requirement is that the cylinder 51 extend radially with respect to the barrel 2.

5 Piston or plunger 50 may be formed of two semi-cylindrical portions which are spaced apart to provide a free flow path for any fluid such as air or oil that may be within the barrel 2 of the hub so that there will be no damping action on 10 the movement of said plunger. Instead of forming the piston 50 of two semi-cylindrical portions it may be of annular construction having one or more passages extending axially therethrough. It will be appreciated that the assembly comprising 15 the pins 47 on the inner ends of the sleeves 7, the links 48, the wrist pin 49 and the piston 50 serve to synchronize movement between the two sleeves 7. The pins, links, plunger and cylinder 51 should be of such size and adequately constructed to take care of the loads that may be 20 imposed thereon due to any tendency for one of the sleeves to be moved out of synchronism with the other by a virtue of forces encountered by the propeller blades which are mounted within 25 the sleeves 7.

The outer portion of the cylinder 51 is provided with a suitable closure member 52 which is secured to the flanged outer end 53 of the cylinder by means of screws 54 which are retained 30 in assembled relationship by means of cotter pins or wire 55. The closure 52 apart from sealing the hub assembly against the leakage of lubricant therefrom also serves as a stop against which the upper surface of the piston 50 abuts 35 to limit the rotary movement of the sleeves 7.

For limiting inward movement of the plunger 50 and rotary movement of the sleeves 7, a semi-cylindrical disc 56 is mounted within the barrel 2. Disc 56 has an outer flanged portion which 40 is received on seat 5 against the shoulder or flange 6. This flanged portion of disc 56 extends about the entire periphery thereof including a transverse, flat portion 57 which serves as an abutment or stop against which the ends of the links 48 45 surrounding the pins 47 may abut.

In addition to serving as an abutment for engagement with the inner ends of the links 48, disc 56 is provided with a central opening surrounded by a fairly wide flange 58 which serves as a guide 50 and seat for loosely receiving the outer element 34 of the adjustable, expandable assembly. The opening surrounded between the flange 58 is coaxial with the barrel 2. Although this opening 55 serves as a guide for the expandable assembly, it permits free floating movement of said assembly axially through the same.

Although the hub herein described is constructed to have both horizontal and vertical balance, it is difficult in practice to produce a hub having exact balance. In order to correct any inaccuracies in balance, the present invention provides on each end of the hub barrel a seat for a balancing weight. As shown in the drawings, each end of the barrel is provided with a flange 59 which serves as a stop against which a split ring or strap 60 surrounding the end portion of the barrel engages. Affixed to each end of the strap 60 is a socket element 61. These socket elements are provided with a centrally apertured closure at one end thereof with their open ends lying adjacent the end of the strap. Said socket elements are arranged to lie in axial alignment when the strap is positioned about the hub barrel to form a receptacle for a plurality of small washer-like lead weights 62. The lead weights

are maintained in stacked relation adjacent one end of the receptacle provided by the juxtaposed socket members. A compression spring 63 positioned between the end of the stock of lead washers and the opposite closed end of one of the socket elements serves to maintain said washers in position. A bolt 64 fitted with a nut 65 passes axially through the sockets and stack of weights and serves to draw the ends of the strap together to bind the same on the hub barrel.

The number of washer-like lead weights positioned in the socket member may be varied to bring the hub into horizontal balance. After the horizontal balance has been effected, one or both of the straps may be rotated about the barrel in the proper direction until vertical balance of the hub is obtained. The straps may then be tightened on the barrel to prevent further displacement by drawing up the nut 65 on the bolt 64.

It will be appreciated from the foregoing description that the present invention provides improved structure for the mounting of blade carrying sleeves within the hub of a propeller for free, unrestricted, synchronized movement therein. In addition, the structure of the present invention provides for the effective sealing of the assembly so that there will be no loss of lubricant from the assembly and yet there will be very little friction between the blade carrying sleeves and the barrel of the hub thereby permitting the blades carried by the sleeves to automatically assume pitch changing positions in response to conditions of flight.

Apart from the foregoing, the present invention provides a simple, novel construction which serves as a stop for limiting rotary movement of the blade carrying sleeves and also serves as a guide for an adjustable, expandable mechanism interposed between the ends of the blade carrying sleeves to load bearings interposed between said sleeves and the barrel of the hub.

We claim:

1. A hub construction for variable pitch propellers comprising a tubular blade mounting member open at both ends for the reception of blade carrying members rotatably mounted in each of said open ends, means associated with the open ends of said tubular mounting member for blocking outward movement of said blade carrying members, a pair of telescoped threadedly interconnected elements, one of said elements engaging the inner end portion of one of said blade carrying members and the other of said elements engaging the inner end portion of the other of said blade carrying members, the inner of said elements having a splined bore and the outer of said elements having a slotted end portion, a locking member having a splined external surface for insertion in said splined bore and a head for engagement with the slotted portion to lock said elements against relative rotation.

2. A hub construction for variable pitch pro-

ppers comprising a tubular blade mounting member open at both ends for the reception of blade carrying members rotatably mounted in each of said open ends, means associated with the open ends of said tubular mounting member for blocking outward movement of said blade carrying members, a pair of telescoped threadedly interconnected elements, one of said elements engaging the inner end portion of one of said blade carrying members and the other of said elements engaging the inner end portion of the other of said blade carrying members, the inner of said elements having a splined bore and the outer of said elements having a slotted external end portion, a bolt-like locking member including a body portion having a splined intermediate portion for reception within said splined bore, a threaded portion at one end and a head at the other end for engagement with said slotted portion, and means cooperating with said threaded end of said bolt-like member to retain said head in locking engagement with said slotted portion.

3. In a variable pitch propeller, a hub having a pair of axially aligned blade-shank-receiving sockets formed thereon, a flanged blade-shank-receiving sleeve mounted for rotation in each socket, a blocking member in each socket, a thrust bearing surrounding each sleeve and interposed between the flange thereof and the blocking member in the socket in which the sleeve is mounted to limit outward movement of the sleeves in said sockets, a second thrust bearing carried by each sleeve at the inner end thereof, a pair of telescoped, threadedly interengaged tubular elements positioned between the inner ends of said sleeves, each of said elements having a journal respectively in one of said last named thrust bearings, said elements being relatively extensible axially by relative rotation thereof to equally urge said sleeves outwardly of the sockets, and a rigid locking member having a non-rotary connection with both of said elements in the extended position thereof to inhibit relative rotation thereof.
